A. E. MADISON.
MARBLE SHOOTER.
APPLICATION FILED JAN. 14, 1919.

1,337,934.

Patented Apr. 20, 1920.

UNITED STATES PATENT OFFICE.

ARTHUR EDWARD MADISON, OF REDLANDS, CALIFORNIA.

MARBLE-SHOOTER.

1,337,934.

Specification of Letters Patent. Patented Apr. 20, 1920.

Application filed January 14, 1919. Serial No. 271,145.

To all whom it may concern:

Be it known that I, ARTHUR E. MADISON, a citizen of the United States, and a resident of Redlands, in the county of San Bernardino and State of California, have invented 5 a new and Improved Marble-Shooter, of which the following is a description.

My invention while capable of discharging various projectiles for different games 10 or contests, is more particularly intended for embodiment in a device for shooting the taw in playing marbles, and the general object of the invention is to provide a shooter presenting a seat for the article to be projected and provided with handles to be grasped for holding the shooter, the handles being relatively movable and the relative movement controlling a spring for exerting a projecting force on the article; together with means to control the spring and 20 to release the same for the projecting movement.

The above and other objects as will appear are attained by the construction and 25 arrangement of parts hereinafter particularly described.

Reference is to be had to the accompanying drawings forming a part of this specification, it being understood that the illustrations are merely practical means for carrying 30 the invention into effect.

Figure 1 is a side elevation of a marble shooter embodying my invention;

Fig. 2 is a plan view thereof;

Fig. 3 is a front view;

Fig. 4 is a partly sectional side elevation showing the parts before the spring is placed under tension;

Fig. 5 is a fragmentary side view showing 40 the spring stressed and ready to be released for discharging the projectile;

Fig. 6 is a sectional plan view on the line 6—6, Fig. 1;

Fig. 7 is a perspective view of one of the 45 leaves of the spring employed in one form of the invention;

Fig. 8 is a perspective view illustrating a modification.

In carrying out my invention in accordance 50 with the illustrated example, a base 10 is provided and formed at the front end at 10^a with a curved seat for the projectile A, here shown as in the form of a ball or marble as employed in playing the game of marbles. At the rear of the base 10, above 55 the same, is a fixed handle 11 rigid with the

base through the medium of a web 11^a rising from said base. Extending upwardly and forwardly from the front end of the handle 11 and web 11^a is an arm 13, to the 60 upper end of which is pivoted as by a pin 14, a second handle 12. The handle 12 is under the pressure of a spring 15 coiled about the pin 14, one end of said spring being carried beneath the handle 12, tending 65 to raise the same, and the opposite end being fixed to the arm 13 as by passing said end laterally through a hole 17 in said arm. A spring 18 in the preferred form of the invention is secured at its upper end to 70 the front of the lever 12 by a clamp plate 19 and screws 20 or the like. The lower end of the spring extends into the base 10 rearward of said seat 10^a to lie adjacent to the seated marble or ball A. The projectile, 75 preferably, is in the form of a steel ball and in practice the base 10 is magnetized for holding the ball on the seat 10^a without other positive holding means. A trigger 21 is provided to control the lower end of the 80 spring, said trigger and the adjacent end of the spring being accommodated in a longitudinal slot 10^c in the base, the trigger being pivoted between its ends to the base by a transverse pin 22. The seat 10^a is formed 85 by the sides of the base at the forward end of the slot 10^c and the seat at the opposite sides of the slot is preferably beveled as at 10^b to permit the ball to be partially received in said slot. The trigger is formed 90 with a lateral handle 23, and is under the pressure of a suitable spring 24 here shown as in the form of a wire having its coiled ends fast on the pin 22, said spring bearing against the top of the trigger forward of 95 the pivot, tending to hold the trigger in engagement with the lower end of the spring 18. Any suitable formation is given to the lower end of the spring and the adjacent end of the trigger to effect an engagement 100 between the spring and trigger, there being shown as one example of means for the purpose, a depending nose 25 on the trigger adapted to be engaged by the upturned or hooked lower end 26 of said spring. 105

With the described construction the marble having been seated on the base at the front, the device is grasped by the handles 11, 12 and the relative movement of the handle 12 and its pivot 14 will serve to stress 110 the spring 18, the trigger retaining its engagement with the spring, and the latter

serving to take a bowed form as indicated in Fig. 5 and in contact with the ball or marble A at the back of the latter. With the spring thus stressed the trigger 21 may be 5 rocked on its pivot by the thumb of the user pressing rearwardly on the handle 23, thereby disengaging the end 26 of the spring from the trigger and permitting the spring to react, to thereby displace the ball A and project the same.

The spring 18 is preferably made up of two or more leaves, three being shown of different lengths, and in practice, one leaf may be arranged to be moved to a position 15 to function with the remainder of the spring or to a position to be out of action and out of the influence of the lever arm 12. Thus, the back leaf 18^a may, as shown in Fig. 7, be formed with a hole 18^b to receive one 20 screw 20 and with a lateral slot 18^c to engage the other screw 20, whereby said leaf may be swung from a position at the back of the spring and in line with the other leaves to dispose said leaf transversely to the 25 remaining leaves and thus exerting no tension. By throwing the leaf 18^a out of action, obviously the strength of the spring will be reduced whereby to modify the projecting force exerted on the ball.

30 In the form shown in Fig. 8, the base 10^e has a short hook-shaped handle 11^e and a larger handle 12^e corresponding with the handle 12. The trigger 21^b is pivoted as at 22^a in the base and its projection 25^a corresponding essentially with the projection 25 engages an upturned hook 26^a of a central loop 18^d formed in a spring 18^e, said spring being coiled about a pivot pin 14^a of the handle 12^e, the coils being disposed at 35 each side of the handle and the ends of the spring being made fast in any suitable manner respectively to the base 10^e and to the pivot shaft 14^a.

I would state in conclusion that while the 45 illustrated examples constitute practical embodiments of my invention I do not limit myself strictly to the mechanical details herein illustrated, since manifestly the same can be considerably varied without departure from the spirit of the invention as defined in the appended claims.

Having thus described my invention, I claim as new, and desire to secure by Letters Patent:

55 1. A shooter of the class described, including a stationary seat for the article to be projected, a spring strip extending at one end adjacent to said seat and adapted to project the article, a trigger engageable by 60 the said end of the spring to hold the latter

adjacent to said projectile seat, and means for bending said spring to stress the same when engaging the trigger, said trigger being movable to release the stressed spring.

2. A shooter of the class described, including a stationary seat for the article to be projected, a spring strip having one end disposed adjacent to said stationary seat, a trigger having a member normally engaging said end of the spring to hold the latter 65 adjacent to said seat, and movable means at the opposite end of said spring to bend the same to stress said spring while in engagement with the trigger, said trigger being subject to the tension of the spring when 70 stressed and being movable to disengage and release the spring.

3. A shooter of the class described, including a seat for the article to be projected, relatively movable handles forming the 80 means to hold the shooter, spring means to project the article, said means being adapted to be stressed by a relative movement of the handles, and a trigger engageable with the spring means to hold the same while being 85 stressed, said trigger being movable to a position to release the stressed spring.

4. A shooter of the class described, including a stationary seat for the article to be projected, spring means adjacent said stationary seat at one end for projecting the article, a handle secured to the opposite end of said spring, a second handle, said handles relatively movable to stress the spring, and a trigger movable to release the stressed 95 spring.

5. A shooter of the class described, including a seat for the article to be projected, a spring adapted to displace the article and project the same, means to stress said spring, 100 and means to release the stressed spring, said spring comprising a plurality of leaves, one of said leaves being movable to a position to function with the remainder of the spring, or to a position to be out of action 105 and out of the influence of the means to stress the spring.

6. A shooter of the class described, having a stationary seat thereon at the front for the article to be projected, a spring having a free end adjacent to the seat at the rear, said spring adapted to be stressed and deformed while contacting with the projectile on the stationary seat, means to stress said spring, and means to release the stressed spring.

7. A shooter of the class described including a magnetized seat for the article to be projected, and means to project said article.

ARTHUR EDWARD MADISON.
